CARD EJECTING MECHANISM

Fred. M. Carroll, Binghamton, N. Y., assignor to
International Business Machines Corporation,
New York, N. Y., a corporation of New York

Application May 25, 1939, Serial No. 275,608

6 Claims. (Cl. 164—112)

This invention relates to card ejecting mechanisms and, more particularly, to the type employed in card punching machines which are utilized to remove the punched cards from the punching mechanisms thereof and into a card receiving hopper.

In key controlled punching machines of the type wherein the cards are manually inserted and manually removed, card ejecting mechanisms are, obviously, not employed. Subsequent improvements in key controlled punching machines incorporated automatic card feed mechanisms whereby the cards are automatically fed from a card supply hopper into an operative relationship with the card punching mechanism. Still further improvements consisted of the addition of a card ejecting mechanism which automatically removed the punched card from the punching mechanism and disposed the punched card into a card receiving hopper. With the understanding that the travel of the card from the card supply hopper to the punching mechanism, then through the punching mechanism by a step by step feeding movement concomitant with successive punching operations, and finally the additional feeding movement for ejecting the punched card out of the punching mechanism, requires the feeding of the card in a direction which is along the longer dimension of the tabulating card, it will be seen that such an arrangement requires a machine of an inordinate length. Punching machines constructed according to this arrangement are not suitable for operation in places such as desks, benches, or other supports of restricted dimensions.

The main object of the present invention is, therefore, to devise a card ejecting mechanism which will eject the card out of the punching mechanism without inordinately increasing the length of the punching machine.

More specifically it is an object of the present invention to eject the card by flipping it over and about its longer dimension thus utilizing some of the space in the punching machine which is not occupied by other mechanisms, and thereby providing a compact machine.

A still further object of the present invention is to devise a card ejecting mechanism which provides a mechanism for automatically shifting the punched card in a horizontal plane so as to shift one end of the card out of cooperation with the punches. When such relationship has been established another automatically operated mechanism will flip the card about its longer dimension thereby ejecting it into a card receiving hopper.

A still further object of the present invention is to provide the punch carriage with a card stop which indicates or defines the proper position of the card with respect to the card carriage and to also provide a mechanism which at the last card column punching position removes the card stop out of cooperation with the card so that the latter may be freely moved in a horizontal plane, independently of the card carriage, out of operative relationship with the card punches.

A still further object of the present invention is to provide a means under control of the improved card ejecting mechanism shown herein for causing the automatic restoration of the card punching carriage, so that this operation, and other related functions, may be performed as in machines of similar construction.

In the drawings:

Fig. 1 is a plan view of the punching machine incorporating the present improvement.

Fig. 2 is a plan view, partially in section, and taken on an enlarged scale with respect to Fig. 1 and shows the left end of the punching machine.

Fig. 3 is a detail view showing the coordination of certain parts of the punching machine.

Fig. 4 is a transverse sectional view taken on the line 4—4 of Fig. 2.

Fig. 5 is a view in front elevation and is taken on the line 5—5 of Fig. 2.

Fig. 6 is a detail view showing one of the contact closing devices and associated electrical contacts.

Fig. 7 is a transverse sectional view taken on the line 7—7 of Fig. 2.

The present improvement is preferably incorporated in a punching machine of a well known type fully shown and described in the patent to Lee et al. No. 1,976,618, dated October 9, 1934.

The cards to be punched are fed from a supply hopper 4 (Fig. 1) to a punching carriage 5. Keys 6 are provided which are manually operated so as to effect the selection and operation of punches 8. As the punches are operated the card carriage is moved step by step under the influence of a conventional escapement mechanism. In this manner the card columns are successively punched. As is well known in the art a punched master card may effect the energization of punch selecting magnets 7 to also effect the operation of the punches 8.

All of the card columns may be punched by the punching machine or after punching a predetermined number of columns the card carriage may be skipped, and in each type of operation the card carriage will move to a "last column" position at which time the improved card ejecting

mechanism will be set into operation so as to remove the punched card from the carriage by an arrangement now to be described in detail.

As best shown in Figs. 4 and 5 to the side frame 10 of the punching machine there is secured a pair of brackets 11, 12 which carry supporting rods 13, 14. A tube 15 loosely surrounds the rod 13 and at its right end the tube 15 has fixed thereto a collar 16 the latter being adjustably fixed to the tube 15 by a set screw 17. One end of a coil spring 18 surrounding the rod 13 securely fits in the adjustable collar 16 and the other end of the coil spring 18 is secured to the side frame 12 and the tendency of the coil spring 18 is to rotate the rod 13 in a clockwise direction, as viewed in Figs. 4 and 7.

A pair of gripper plates 19 have their ends 20 curved around the tube 15 and are normally in the position shown in Figs. 1 and 7 but are rocked by the rocking of tube 15 to the dotted line position shown in Fig. 7. Secured to the tube 15 is a collar 21 held to the tube by a set screw 22 (Fig. 2) and said collar has a projection 23 which, as shown in Fig. 7, is interposed between the gripper plates 19 to rock the plates 19 by the rocking of the tube 15. A cylindrical spring 24 shown in Fig. 5 is fixed to the curved ends 20 of gripper plates 19 so as to rock them together and securely grip the punched tabulating card 25 as the latter is interposed between the gripper plates 19 as successive card punching operations ensue. A projection 26 of the collar 21 normally rests, as shown in Figs. 2 and 5, on the horizontal edge 27 of a cam plate 28 which is pivoted on the rod 14 and urged by a coil spring 29 to the position shown in Fig. 7.

Secured by screws 30 (Figs. 2 and 5) to the bracket 11 is a tube 31 and a coil spring 32 surrounds the tube 15 and is within the tube 31. One end of the spring 32 bears against a fixed bracket plate 33 which is apertured to receive the tube 15 and the other end bears against a collar 34 secured to the tube 15. The spring 32 urges the tube 15 and parts carried thereby to the left so that the gripper plates 19 now engaging the punched card 25 shifts the punched card to the left clear of the punches 8, since in the last column punching position the card is not free of the punches or other guide plates of the 50 punching machine.

The shifting of the card is normally prevented by a latching mechanism comprising an extension 35 of a pivoted release arm 36. The arm 36 is rocked by the following described means. The release arm 36 is pivoted by a stud 37 carried by a bracket 38 and at a certain position of the carriage its rear end underlies an operating arm 39 which is pivoted on a rod 40 carried by the card carriage. The arm 39 carries a block 41 (Figs. 2 and 4) and the left edge of the tabulating card 25 bears against this block to align the card on the card carriage. When the card carriage is skipped or moved to the last column position the arm 39 engages a fixed cam plate 40 (Fig. 4) which rocks the free end of arm 39 downwardly to lower block 41 out of engagement with the tabulating card 25 and since the arm 39 now overlies, as shown in Fig. 2, the left end (Fig. 4) of the release arm 36 the latter will be rocked to release spring 32 for action, so as to cause the punched card to be moved laterally over the card carriage entirely clear of the punches 8 and without obstruction by the block 41.

Projection 26 slides during this operation to

the left (Fig. 5) until it reaches an inclined edge 42 of the plate 28 thus permitting spring 18 to rock the tube 15 and thus the ejector plates 19 are flipped during their lateral movement to the dotted line position (Fig. 7) placing the laterally shifted punched tabulating card over a storage hopper 43. The card is positively stripped from the ejector plates 19 by means now to be described.

As best shown in Fig. 3 the escapement rack 44 of the card carriage carries a pawl 45 pivoted at 46 to the escapement rack. As the escapement rack 44 and the card carriage move laterally beyond the last column position, as just described, the pawl 45 will be moved from the dotted line position shown in Fig. 3 to the full line position shown in this figure and in so doing it will engage a lug 47 of an arm 48 secured to a rock shaft 49, and the pawl 45 will rock idly counterclockwise past the lug 47 and occupy the full line position. By means to be shortly described, the escapement rack is moved to the right by the power restoration of the card carriage in the same direction so that pawl 45 will strike the lug 47 but since the pawl 45 will now be prevented from rocking clockwise, since it engages a pin 50 carried by the escapement rack, the movement of the latter to the right will cause the rocking of the arm 48 and, therefore, the shaft 49.

Pivots mounted on the rod 14 and urged by a coil spring 51 (Figs. 2 and 5) is a bail 52 which carries a pair of upstanding stripper fingers 53. When the card has been flipped in the manner just described the stripper fingers 53 will cooperate with one of the longer edges of the tabulating card. As best shown in Figs. 4 and 5 the bail 52 is provided with a bail extension 54 which cooperates with a profile cam 55 secured to the rock shaft 49. As the shaft 49 is rocked the cam 55 will rock the bail 52 and by means of the stripper fingers 53 positively remove the tabulating card out of cooperation with the ejector plates 19. In the operation of the machine the stripper fingers 53 are given a rapid operation so as to quickly strip the card from the ejector plates 19 so that the stripped card will fall freely into the storage hopper 43.

It was previously stated that when the ejector plates 19 are released for lateral movement, the lug 26 will slide along the horizontal edge 27 of the cam plate 28, and thereafter down the inclined cam edge 42 thereby causing the ejector plates to be rocked to the dotted line position shown in Fig. 7. When in the dotted line position the lug 26 will strike a lug 56 of a bracket 57 (Fig. 7) secured to the side frame 10 of the punching machine, in which position it will be entirely free of the cam plate 28. After the shaft 49 has been rocked to cause the stripper plates 53 to strip the flipper card from the ejector plates 19 said rocking being by contacts 201 closed by a lug 62 on disc 59, as later described, arm 58 secured to the shaft 49 will strike a disc 59 secured to the tube 15 by a set screw 60 and 65 engaging the side face of the disc 59 it will restore the tube 15 to the right, as viewed in Fig. 5. The lug 26 will thereupon engage a cam edge 61, Fig. 7, of the bracket plate 57 and the cam edge 61 is spirally formed as best shown in Figs. 2 and 7, thereby causing the tube 15 to be reversely rocked. The lug 26 will, during this operation, be positioned underneath the cam plate 28 thereby rocking it clockwise as viewed in Fig. 7 until the lug 26 clears the horizontal edge 27 75

of the cam plate 28 thereby relatching the ejector plates 19 in normal position as shown in Fig. 7. The parts are now in the normal position placing them in readiness for a subsequent card ejecting operation.

As best shown in Fig. 6, the disc 59 which, as previously stated, is fastened to the tube 15 which is moved laterally, and also rocked in a clockwise direction as viewed in Fig. 6, is provided with 10 a pin 62 which is adapted to engage a spring blade of contacts 201 thereby closing such contacts and as is well known and fully described in Patent #1,976,618 a circuit to a magnet 175 (Fig. 1) which causes the power restoration of 15 the punching carriage and by means of said punching carriage effect the rocking of the shaft 49 to perform the functions effected by the rocking of this shaft.

From what has been previously stated the closure of contacts 201 (as well as last column contacts 191, Fig. 1) will effect the energization of the magnet 175, which is shown in Fig. 1. The magnet 175 will thereby attract its armature 176 to rock an arm 185 to close contacts 190. The 25 closure of the contacts 190 will close an electrical circuit to the motor 157. Contacts designated 190, 191, and 201 herein correspond to contacts similarly designated in Fig. 15 of the patent to Lee et al. #1,976,618, and the same applies to 30 the designation of the motor 157. The manner of closing contacts 190 is fully described and shown in Fig. 1 of this patent.

As more fully described in this patent, the energization of the magnet 175 will rock an arm 35 177, shown in Fig. 1, and which corresponds to the arm designated by the same numeral in Fig. 9 of the patent. The rocking of this arm will effect a clutch connection between the driving shaft 161, Fig. 1, of the motor 157 and a driven shaft 162. By effecting the clutch connection, shaft 162 is rocked and also a gear 163, and which gear corresponds to the gear similarly designated in Fig. 3 of the Patent #1,976,618. As more fully described in this patent the rocking of the gear 40 just mentioned will cause a power restoration of the card punching carriage at which time another card will be removed from the card supply hopper to the punch carriage preparatory to punching a successive tabulating card.

While there has been shown and described and 50 pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following 55 claims.

What is claimed is:

1. In a card handling machine, means comprising a pair of pivoted jaws for receiving a card ejected from a punching mechanism and means 60 for moving said jaws along their pivot to remove the punched card from the punching mechanism, and means for thereafter swinging said jaws in an arc about their pivot to deposit the punched card in a receiving receptacle.

2. In a card handling machine, a punching carriage carrying a card which is moved step by step concurrently with successive card punching operations, means for removing the punched card from said card carriage comprising a gripper receiving said punched card and means for moving said gripper to move the card in the same plane in which it is moved step by step, means controlled by said carriage and responsive to a predetermined position of said carriage for causing the operation of said moving means, and means separate from the moving means for swinging said gripper about an arc while carrying the card to deposit the punched card in a receptacle.

3. A card ejecting mechanism adapted for cooperation with a movable carriage to eject cards therefrom, said ejecting mechanism comprising a gripping means including a pair of pivotally mounted jaws, means for moving said jaws along their pivot to move the card in a horizontal plane, means responsive to a predetermined position of the card carriage for operating said moving means, and means for causing the rotation of said jaws during their movement along their pivot to rotate 25 said punched card in an arc to deposit it in a receiving receptacle.

4. A card ejecting mechanism adapted for cooperation with a movable card carriage to eject cards therefrom comprising a pair of card receiving grippers pivotally mounted on a rod and slidably mounted along said rod, means for effecting a slidable movement of said gripper along said rod and means for concurrently causing said gripper to be rocked about said rod during said 30 slidable movement, both component movements of said gripper removing the punched card from said carriage and concurrently depositing it in a receptacle.

5. In a card handling machine, a card carrying carriage, a pivoted arm having an abutment cooperating with a marginal edge of the card for defining the proper location of the card with respect to the card carriage, a pivoted gripper receiving said card and means for moving said gripper to move the card in a horizontal plane, means for operating said arm at a predetermined position of the carriage for displacing said abutment to release the card and for causing the 45 operation of said moving means, and means for swinging the gripper in an arc about its pivot and while carrying the card to deposit the punched card in the receptacle.

6. In a card handling machine including a step by step operated punch carriage carrying a card to be punched, a power driven card carriage returning means, means for removing the punched card from said carriage in the same plane in which it is moved for punching comprising a pivoted gripper and means responsive to a predetermined position of said carriage for moving said gripper along its pivot, means for automatically causing the rotation of said gripper about its pivot to deposit the punched card in a receptacle, and means operated concurrently with the rotation of said gripper for causing the 55 operation of the carriage returning means.

FRED M. CARROLL.
